UNITED STATES PATENT OFFICE

2,338,707

VALVE LATCH DEVICE FOR PNEUMATIC
PISTON PUMPS, DIFFERENTIAL TYPE

Alexander Boynton, San Antonio, Tex.

Original application January 31, 1939, Serial No.
253,876. Divided and this application March
30, 1942, Serial No. 436,911

2 Claims. (Cl. 277—20)

This application is a division of my copending application Serial Number 253,876, filed January 31, 1939, and entitled "Pneumatic piston pump, differential type."

My invention relates to a means for lifting liquids from wells and of propelling liquids through pipe lines by the force of compressed air or gas acting under or behind a slug of liquid previously admitted into the eduction tube of a well or into a pipe line by the automatic action of valves which alternately admit a slug of liquid of predetermined weight and then admit under or behind the slug enough compressed air or gas to expel it from the well or pipe line.

The slugs of liquid are admitted into the eduction tube of a well or into a pipe line by means of a valve that controls the admission of liquid thereto (hereinafter referred to as the liquid intake valve) after a valve that controls the admission of air or gas thereto (hereinafter referred to as the air or gas valve) moves from one seat, referred to as the first seat, and closes upon another seat, referred to as the second seat. The air or gas valve and the liquid intake valve are urged to the only position in which they are both closed by a spring which may work in conjunction with a latch; the latching means tending to hold the air or gas valve and the liquid intake valve closed in the first position, and tending to hold the air or gas valve closed in the second position while the liquid intake valve is open. The force of the air or gas is utilized to hold the air or gas valve seated upon the second seat while the slug of liquid to be expelled is entering the eduction tube or pipe line through the liquid intake valve. The weight or back pressure of the slug of liquid thus admitted into the eduction tube or pipe line is utilized to unseat the air or gas valve from its second seat, and to hold the air or gas valve open intermediate its two seats, while, in that position, the liquid intake valve cuts off the admission of more liquid until the slug has been expelled; whereupon the air or gas valve again assumes the closed position upon its second seat with the liquid intake valve open. This cycle is automatically repeated during the period of operation.

An object of the invention is the provision of new and improved latching means for holding the air or gas valve and the liquid intake valve closed in one position and for holding the air or gas valve closed and the liquid intake valve open in another position.

With the above and other objects in view this

invention has particular relation to certain novel features of construction, operation, and arrangement of parts which manifestly can be changed and combined in different ways within the scope and purpose of this invention.

Other objects and advantages of this invention will be apparent from the following description as illustrated in the accompanying drawings in which:

10 Fig. 1 is a vertical section of a well equipped with this device.

Fig. 2 is a vertical section of the preferred form of the device.

Fig. 3 is an enlarged vertical section of one embodiment of the latching means in one of its positions.

Fig. 4 is a view similar to Fig. 3 showing the latching means in its other position.

Fig. 5 is a cross-section on the line 5—5 of Fig. 3.

Fig. 6 is a detail elevation of the ball roof member.

Fig. 7 is a vertical section of a modified form of the invention.

Identical characters are employed to designate and refer to corresponding parts throughout the drawings.

Fig. 1 shows a well equipped with this device in which the outer casing 1 is sealed above the ground surface G by the casing head 2 having two openings, one of which is closed by the bull plug 3, the other being connected with the pipe line 4 for the purpose of conveying away gas produced by the well. The pressure tubing 5 is suspended centrally within the casing 1 and proximate its upper end rests upon the plate 6 to which it may be welded or otherwise joined in leak proof contact therewith. The cap 7 is then screwed down upon the lead ring 8, at the same time compressing the lead ring 8, to form a seal against the escape of formation gas from the well. Any other casing head arrangement that will afford a seal between the well casing and the pressure tubing may be used; many such casing heads being well known to the art.

The pressure tubing 5 extends above the casing head 2 and is connected by means of the coupling 10 with the T 11, having a lateral branch 11a connected to the air or gas pipe line 12. The upper end of said T is formed to support the eduction tubing 13 which is closed about hermetically by the packing gland 14. The pressure tubing 5 may be of one diameter throughout its length or it may be swaged to a different diameter for part of its length as shown.

The pressure tubing is connected at its lower end to the swaged coupling 16 which has the tapered seat 16a to be engaged by the lead seal 17, secured upon the eduction tubing proximate the lower end thereof. The lower end of the swaged coupling 16 is connected to the tubular housing 18, which is connected at its lower end to the coupling 19.

Within the housing 18 is the seal valve 20, held resiliently upon the upper end of the seal valve spring 21 to normally engage the seal valve seat 16b at the lower end of the swaged coupling 16. Said spring 21 rests upon the annular plate 22 in the coupling 19. Below the coupling 19 the tubing may be extended downwardly as far as is desired.

While the pressure tubing 5 is being lowered into the well, the seal valve 20 contacts the seal valve seat 16b upon which it is held by force of the spring 21, plus the fluid pressure in the well. When the eduction tubing 13 is lowered into the position shown in Fig. 1, the slotted extension 28a forces the seal valve down to the position shown in Fig. 1, whereupon well liquid is freed to enter the device. This action of the seal valve 20 which keeps well liquid out of the pressure tubing while the eduction tubing is being lowered or withdrawn is very important, in that high flow starting pressures are thereby avoided, as is explained in my prior Patent 2,104,008.

Compressed air or gas is supplied into the pressure tubing from an outside source through the pipe line 12 if the well does not produce enough gas to flow it, as was illustrated in my prior Patents 2,042,583 and 2,104,008.

The lead seal 17 forms the barrier which confines compressed air or gas within the annular space between the pressure tubing 5 and the eduction tubing 13. The nipple 26 also contains the pressed in liquid intake governor 48, further held in place by the pressed in check valve seat 47 upon which the check valve 46 normally engages, as clearly appears in Fig. 2. The lower case nipple 37B, the air or gas intake connection member 27, the upper case nipple 37A, the connection and valve sleeve member 36, and the eduction tubing connection 35, all threaded joined together as shown in Fig. 2, constitute the outer shell of the device which is threaded joined to the eduction tubing 13.

The air or gas intake connection member 27, serves as a connection between the lower half of the device containing the liquid intake governor, check valve, and latch assembly and the upper half of the device containing the three valves and related parts. It will be noted that the air or gas may enter the device from the pressure tubing through the ports 27a and that the well liquid may also enter through the separate longitudinal passages 27b.

The air or gas valve first or lower seat member 59 furnishes the first or lower seat for this valve as shown at 59a. The air or gas valve 28 is threaded connected to the latch shaft 40, as shown in Fig. 2. The air or gas valve shank 28c fits within the central longitudinal bore through the liquid intake slide valve 30. This valve is locked over said shank and upon the shoulder 28b of the air or gas valve member by the threaded engagement between the shank 28c and 31a, as appears in Fig. 2.

A metallic ring 32 forms the upper support for the yieldable ring 33, the lower support for this ring being a conforming recess in the upper end of the connection and valve sleeve member 36.

The valve 31 has a close working fit within the rings 32 and 33. The slide valve 30 has a close working fit within the central bore through the sleeve member 36 and the opening through the valve housing member 29 above the air or gas valve second or upper seat 29a. The valve 28 has the clearance 29b around it for the purpose of allowing the passage of sufficient compressed air or gas from the pressure tubing into the eduction tubing to expel the liquid slugs, as will be described later.

It is desirable that a latching means be employed to cause snap action of the valves. A latch similar in construction and operation to the one here shown appears in my prior Patents Nos. 1,968,633; 2,006,909; 2,010,135; 2,042,583; 2,054,924; and 2,104,008.

The latch housing nipple 38 is threadedly connected to the lower boss 27f of the connection member 27 and is closed at its lower end by the chamber plug 45, the latch sleeve 44 being pressed in as appears in Fig. 2. The upper end of the latch spring 39 engages a recess in the boss 27f and the lower end rests in a depressed annular shoulder formed upon the upper end of the ball roof 41, which engages the latch balls 43 upon the ball floor 42, locked in place upon the shaft 40 by the nut 58. It will be noted that the surfaces engaging the latch balls are inclined, so as to force the balls outward to engage the sleeve 44 by whatever force may be imparted by the spring 39, always installed under some compression. It will be noted further that the length of the sleeve 44 is such as will allow the latch balls to roll slightly over its top end on the up stroke and to roll slightly under on the down stroke of the valves.

The force which the latch employs at either extreme of the valve travel is determined by the expansive force of the spring 39 and by the magnitude of the horizontal movement over either end of the sleeve 44, as well as by the length of the radius describing the arcs forming the ends of this sleeve. The longitudinal openings 44a provide for free circulation of a lubricant that should be placed within the nipple 38 to facilitate smooth working of the latch. Slight clearance at 27d' is provided between the latch shaft 40 and the central longitudinal bore in the connection member 27 to keep foreign substances out of the latch and to provide that the latch mechanism will not become impinged upon fluid on the down stroke of the valves or tend to create a partial vacuum on the up stroke. The portion of reduced diameter 40a provides that the clearance between these members is many times greater, except at the beginning and at the completion of each stroke. The normal position of the shaft being as shown in Fig. 2, it is apparent that a lubricant of proper viscosity in the latch chamber will not leak out while the device is in transit or in storage during the interval between manufacture and installation.

The check valve 46 prevents compressed air or gas from migrating out of the device into the lower regions of the well where such air or gas might retard or hold back liquids moving into the well.

The slotted openings 48a in the liquid intake governor 48 are of such restricted area as to slow down the movement of well liquid through the device, in order to prevent abrasive substances from unduly damaging the exposed parts.

The device shown in Fig. 2, being installed in the bracketed space A, Fig. 1, all valves will

remain closed until compressed air or gas is turned into the pressure tubing 5 via the pipe line 12 and the pressure entering beneath the valve 28 via the ports 27a and the annular passage 27d is built up high enough to spring the latch and drive the valve 28 from its first or lower seat 59a to its second or upper seat 29a.

It is presumed that the latch is adjusted to hold the valve 28 upon its first seat with enough force to compress the spring 39 the full distance of the valve travel when the latch releases. The valve 28 then will remain seated upon its second or upper seat 29a until enough well liquid enters the eduction tubing to exert sufficient back pressure upon the top of the valve 28 to unseat it, with the aid of the expansive force of the spring 39. When the air or gas valve 28 is engaged upon its second seat 29a, the latch, being in the position shown in Fig. 4, should hold with enough force to produce sufficient recession of the valves to close the valve 30 by forcing the lower end of it down past the inclined opening 36d when the latch releases.

It should be noted here that more downward movement is required to close the valve 31 than will be required to close the valve 30. When the liquid intake valve 30 and the leakproof valve 31 are wide open, that is when the air or gas valve 28 is upon its upper or second seat, well liquid enters the eduction tubing via the perforations 24a, through the spring 21, between the fins 20a, by the valve 20, through the slots 26b and the liquid intake governor slots 48a, by the check valve 46, through the longitudinal passages 27b, the opening 36d, through the openings 30b of the slide valve 30, and by the valve 31.

It will be noted that all valves move in unison, that the air or gas valve 28 is closed in both positions of extreme travel, and that a slight recession of the valves from their extreme upper positions opens the air or gas valve 28, closes the liquid intake valve 30, and leaves the valve 31 still open. The extreme upper position of the lower ends of the valves 30 and 31 are shown at D and F, respectively. The level to which these valves recede in order to close the liquid intake is indicated at E and J, respectively. The clearance 29b between the valve 28 and its chamber is sufficient to allow enough compressed air or gas to pass through this clearance to flow the well whenever the valve 28 is positioned intermediate of its seats 59a and 29a. Each time a slug of well liquid enters the eduction tubing and is expelled as stated, the air or gas valve 28 seals off upon the seat 29a; thus again opening the liquid intake and repeating the operation as long as well liquid and compressed air or gas are supplied to the device.

The relation of the three valves and the function of each will be stated now. The valve 28 controls the admission of compressed air or gas from the pressure tubing 5 to the eduction tubing 13. On its first seat 59a this valve constitutes a barrier against the well liquid (if any should leak past the valve 30) entering the pressure tubing while the well is standing between operating intervals. In this connection it is proper to observe that many oil wells of small production are flowed at intervals, sometimes several hours or even days apart.

During these intervals it is important that no well liquid be allowed to enter the pressure tubing because this would increase the air or gas pressure required to initiate the flow. On its second seat 29a the valve 28 prevents the com-

pressed air or gas in the pressure tubing from aerating the liquid slug while the same is entering the eduction tubing. The valve 28 is the first of the three valves to open on the up stroke and the last to close on the down stroke.

The slide valve 30, which controls the admission of well fluid to the eduction tubing, is closed (covers the opening 36d) when the air or gas valve 28 is engaged upon its first seat 59a, as appears in Figs. 2 and 7. This valve 30 is open, the lower end being at the level D when the valve 28 is closed upon the seat 29a. The slide valve 30 again closes at slight downward movement of the valve 28 away from its seat 29a, this closure taking place at the level E. With relation to the other two valves 28 and 31, the valve 30 is the last to open on the up stroke and the first to close on the down stroke. The office of the leak proof valve 31 is to prevent well liquids that may leak past the valve 30 from entering the eduction tubing while the device is not being operated. In the closed position shown in Fig. 2, fluid leaking past the valve 30 enters the transverse ports 36a, the annular space 36b, and the open space 36c to contact the outer surface of the yieldable ring 33; thereby to cause the inner surface of this ring to seal tightly against the valve 31. Obviously the greater such pressure the tighter will be the seal produced thereby. On the up stroke of the valves, this valve is the second to open, the first to open being the valve 28. On the down stroke the valve 31 is second to close, the first to close being the liquid intake valve 30, and the last to close being the air or gas valve 28, then contacting the seat 59a.

From the foregoing it may be stated concisely that on the up stroke, the valves open in the following order: 28-31-30, and that they close on the down stroke in the order of 30-31-28.

The difference between the weight of the slug and the air or gas pressure used to expel it equals, and is determined by, the force required to compress the spring 39 far enough to allow the valve 28 to contact the seat 29a, plus whatever force the latch employs in the uppermost position of the valves. The weight of the slug, therefore, may be increased by increasing the air or gas pressure, and vice versa. Increasing the air or gas pressure decreases the percentage of difference between the air or gas pressure and the weight of the slug, and vice versa, while the actual difference between them remains constant.

The device and all modifications thereof shown in this application may be installed in all the ways shown in my hereinbefore mentioned patents.

Fig. 7 shows a modified form of the invention shown in Fig. 2, and which may be installed within the bracketed space A, Fig. 1, in the same manner and operated in the same way as was described for the device shown in Fig. 2.

It will be noted that the latch assembly in Fig. 7 is different in construction and position from the one shown in Fig. 2. The eduction tubing connection 35A houses the pressed in metallic ring 32, the yieldable ring 33, and its lower extension is internally threaded to engage the metallic ring 34, which holds the yieldable ring 33 in position, as shown in Fig. 7. Fluid pressure is transmitted to the outer surface of the yieldable ring 33 through the annular space 35b and the transverse ports 35a, in order to cause the liquid intake leak-proof valve 31A to be gripped in sealing engage-

ment by the yieldable ring 33, if fluid under pressure should leak past the valve 30, as was explained for the very similar valve 31 in Fig. 2.

The latch shaft 40A, locked in position by the nut 57, contacting the lower internal boss 27g, supports the plate 52, to which it is soldered or welded at 52b. This plate is in turn soldered or welded into the lower end of the latch assembly nipple 51 at 52a, which nipple it hermetically closes. The upper end of this nipple is closed by the plug 50. The latch spring 39 fits into a circular recess in the lower end of the plug 50. The latter spring, under some compression against another circular recess in the upper end of the ball roof 41, urges the latch balls 43 downward against the ball floor 42A, which is threadedly secured upon the lower end of the latch carrier shaft 49 and is locked in place by the solder 42a.

The latch balls are urged outwardly by the beveled surfaces of the ball roof and the ball floor to contact the pressed in latch sleeve 44, over the convexly curved ends of which sleeve the latch balls rolls at each end of the valve travel. The latch shaft 40A may be adjusted upward or downward by means of the enlarged threaded lower end, the adjustment being secured by the lock nut 57. Adjusting the shaft 40A upward, moves the latch sleeve 44 higher, causing the latch balls to engage more upon the lower end and less upon the upper end thereof as the latch operates. Adjusting the latch shaft downward produces the opposite effect upon the latch, as is apparent in Fig. 7.

The threaded connection between the latch carrier shaft 49 and the lower enlarged end 31c of the valve 31A provides the connection between said valves and the latch, the reduced portion 31b being to enable the valve 31A to open at proper travel on the up stroke of the valves. It will be observed that the enlargement 31c is also threadedly connected to the housing nipple 38, which has an easy working fit over the nipple 51, the lower end of the nipple 38 being threadedly connected to the guide plug 53, into which plug is threaded the valve sleeve 54, locked by the nut 55.

It will be noted that the air or gas valve 28A is threaded upon the lower end of the sleeve 54, spaced apart from the slide valve 30 by the spacer nipple 56. The valve 30, which has a close working fit within the central bore through the connection and valve sleeve member 36A and has a similar fit within the central bore through the upper end of the housing member 29, has a central opening which provides a close fit over the lower end of the sleeve 54, the upper end of the valve 30 being supported by the shoulder 54a. The central bore through the valve 28A and through the sleeve 54 providing an easy working fit over the shaft 40A, and the nipple 38 being free to move over the latch nipple 51, the three valves assembly is as free to operate as was described for the action of the device shown in Fig. 2.

The latch assembly nipple 51 may be filled with a lubricant to lubricate the latch. It will be noted that the lower portion of the shaft 49 is of reduced diameter, the reduction being slightly below the top of the plug 50. This is provided so that the latch will breathe while operating. On the up stroke of the valves, slight movement elevates the lower end of the enlarged portion of the shaft 49 above the plug 50, the reduced section having large clearance in the central bore through the plug 50, fluid will rush into the latch

chamber to compensate for the outgoing movement of the shaft 49. On the down stroke of the valves, this opening through the plug 50 is not restricted by entrance of the enlarged upper portion of the shaft 49 until near the end of the stroke, the slight displacement resulting from the remainder of the down stroke being allowed to escape through the small clearance which should be provided between the enlarged portion of the shaft 49 and the bore through the plug 50.

This arrangement for accommodating the displacement within the latch housing while the device is in operation, also provides against leaking of the lubricant out of the latch chamber

15 during transportation and handling of the device between the point of manufacture and the well in which it is to be installed, the breather space being so slight that a lubricant or proper viscosity will not leak out even though the device be allowed to stand upside down. The longitudinal openings 44a likewise facilitate the free movement of the latch by providing that the lubricating fluid may circulate around the latch sleeve 44 when the latch acts, as in Fig. 2.

20 It will be observed also that the air or gas intake connection member 27A provides the entrance ports 27a for the air or gas and the longitudinal passages 27b for the well liquid.

An important difference between the constructions of these devices is that in Fig. 2 the latch shaft 40 and all valves are joined together and move in unison, without being fastened to any other member; whereas in Fig. 7 the latch shaft 40A is threadedly connected within the intake connection member 27A.

25 Another structural difference is that the latch assembly depends below the connection 27 in Fig. 2; whereas in Fig. 7 this assembly is standing above the connection member 27A. Of 30 some further importance in making sure that no foreign substance will foul the latch assembly, is the fact that the latch assembly nipple 51 in Fig. 7 is itself completely housed within the latch housing nipple 38.

35 It is obvious that mechanical changes may be made in the structure, and that equivalents may be substituted for the parts shown; and I reserve the right to make such mechanical changes, substitutions, and adaptations within 40 the scope of the invention as comprehended by the appended claims.

I claim:

1. A latch device for yieldably holding a valve system in either one of two limit positions of 45 longitudinal movement, said latch device comprising: a stem; a ball floor member secured on said stem; a ball roof member mounted on said stem to slide toward or from said floor member; a compression spring on said stem adapted to

50 press said roof member toward said floor member for all positions of said stem; a latch sleeve; means for holding said sleeve in a fixed position around said stem and members; one or more balls adapted to be forced by said floor and roof members

55 against said sleeve and to engage one of the ends of the sleeve for determining either of said valve positions; a fixed abutment for the opposite end of said spring, whereby the spring performs the dual function of forcing said balls into

60 engagement with the latch sleeve and moving the valve system in one direction.

65 2. A latch device for yieldably holding a valve system in either one of two limit positions of longitudinal movement, said latch device comprising: a stem; a ball floor member secured on said

stem; a ball roof member mounted on said stem to slide toward or from said floor member; a spring adapted to press said roof member toward said floor member at all positions of said stem; a latch sleeve mounted around said stem and members; one or more balls adapted to be forced by said floor and roof members against said sleeve and to engage one of the ends of the sleeve for either of said valve positions; means for holding said sleeve in adjustable longitudi-

10

nal position relative to said stem to vary the relative latching effect of the balls on the ends of the sleeve for the two limit positions of the valve system; a relatively fixed abutment for the opposite end of said spring, whereby the spring performs the dual function of forcing said balls into engagement with the latch sleeve and moving the valve system in one direction.

ALEXANDER BOYNTON.
